UNITED STATES PATENT OFFICE

ERNEST D. SIMONS, OF CHESHIRE, CONNECTICUT, ASSIGNOR TO SCOVILL MANUFACTURING COMPANY, OF WATERBURY, CONNECTICUT, A CORPORATION OF CONNECTICUT

PEARL CAP SNAP FASTENER SOCKET MEMBER

Application filed March 11, 1930. Serial No. 434,988.

The object of this invention is to provide a pearl or other ornamental cap for snap fastener socket members which may be used upon fine articles, such as dress shirts, that are to be laundered, the construction being such as to minimize if not practically prevent injury to the fastener in the washing and ironing operations.

The invention consists of a snap fastener socket member, having a cap or top piece of pearl or other ornamental material, to which a resilient stud-engaging element is secured by means of a ring applied externally to the cap or top piece and the resilient element and which is adapted to receive between itself and the resilient element an attaching eyelet, so that the resilient element is practically concealed within the eyelet and is therefore protected against injury by the washing and ironing machines, as I will proceed now to explain more fully and finally claim.

In the accompanying drawings illustrating the invention, in the several figures of which like parts are similarly designated, Figure 1 is a top plan view of the cap or top piece and Fig. 2 is a cross section thereof. Fig. 3 is a bottom plan view of the resilient stud-engaging element and Fig. 4 is a cross section thereof. Fig. 5 is a bottom plan view of the connecting ring and Fig. 6 a cross section thereof. Fig. 7 is a top plan view of a preferred form of eyelet. Fig. 8 is a cross section of the device mounted or set. Fig. 9 is a cross section of one form of a complementary stud member.

The cap or top piece 1, is shown as of concavo-convex form, and it may be of any other form and suitably ornamented or decorated and of any material suitable for use on an article to which the device is to be applied. If such article is a dress shirt, for example, this piece 1 may be of pearl or any other material, natural or artificial. The bottom of this cap or top piece is undercut or hollowed out, as indicated at 2, in order to afford plenty of room for the entrance of the complementary stud member without pressure upon the cap or top piece.

The resilient stud-engaging element com-

prises an outwardly turned curved flange 3 and a depending barrel 4 which is slotted longitudinally at a plurality of points, as indicated at 5, and has its lower slotted edge 6 turned inwardly so as to afford a medium for engaging the neck 7 of the stud 8 to hold together the two parts on which the respective fastener members are set. The flange 3 surrounds or encircles the undercut portion of the cap and has only surface contact with the cap.

The cap or top piece 1 and the resilient stud-engaging member, are united by a ring 9 the lower edge 10 of which is curved inwardly and the upper edge 11 of which is adapted to be spun or otherwise closed around and applied to the lower edge of the cap or top piece 1, as shown in Fig. 8, sufficient space being provided between the in-turned edge 10 of the ring and the flange 3 of the resilient stud-engaging element to receive the barrel 12 of the fastening eyelet 13, which latter may be of usual construction, the end of said barrel being turned outwardly by the flange 3 and thus clinched between the ring and the stud-engaging element to attach the parts to the material 14 as shown in Fig. 8.

The attaching eyelet may have its flange provided with prick points 15 in order to engage the material to which the device is applied and prevent its turning therein.

It will be noted from Fig. 8 that the bottom of the stud-engaging element is confined within the attaching eyelet, so that there is no external projection of said element that might be damaged in washing or ironing when the device is applied to an article that must be laundered.

Variations in the details of construction are permissible within the principle of the invention and the scope of the claim following.

What I claim is:—

A snap fastener socket member, having an ornamental cap or top piece provided with an undercut bottom to afford clearance for a complementary stud member, a resilient stud-engaging element having a barrel slotted at a plurality of points and an outwardly curved

flange arranged in surface contact with the bottom of the cap or top piece and encircling its undercut portion, and a connecting ring applied externally to the lower edge of the cap or top piece and having its lower edge curved inwardly beneath the flange of the resilient stud-engaging element, a space being left between the said flange and the bottom of the connecting ring to receive and clinch an attaching eyelet, combined with said eyelet when set and within which eyelet said stud-engaging element is confined so as to avoid its external projection beyond the eyelet, whereby damage to the stud-engaging element is prevented.

In testimony whereof I have hereunto set my hand this 7th day of March A. D. 1930.

ERNEST D. SIMONS.
